MANUFACTURING PROCESS

Carl J. Linxweiler, Richard Y. Moss, and Jacob T. Welch, Dayton, Ohio, assignors to The Sheffield Corporation, Dayton, Ohio, a corporation of Ohio

Application June 3, 1946, Serial No. 674,014

3 Claims. (Cl. 51—281)

1

This invention relates to the manufacture of cooperating matched members of complementary form or shape.

One object of the invention resides in the method of making a grinding wheel having a peripheral grinding surface which is complementary to the form of another grinding wheel and in which all the form variations, however small, of one of the wheels are accurately reproduced on the other grinding wheel.

Another object resides in the method of making a pair of matched grinding wheels of complementary form in which one grinding wheel is employed to form a cutting tool from which a rotatable grinding wheel crusher roll is made, and the crusher roll is then employed in pressure contact with the second grinding wheel so that the form given to the surface of the second grinding wheel is exactly complementary to the form on the first grinding wheel.

Another object resides in the method of making a pair of cooperating interfitting members, in which the members are ground from grinding wheels of exactly complementary shape, one of the grinding wheels being formed by a crusher roll which is cut or turned by a form cutting tool made by the other grinding wheel.

Another object resides in the method of making a pair of matched grinding wheels of complementary form in which a crusher is used to form one of the grinding wheels which can reproduce one or more additional crushers or form tools of the same form as the first crusher. One of these form tools is used to produce a crusher of the same form as the grinding wheel mentioned and this crusher is then used to form the second grinding wheel of a form complementary to the first grinding wheel.

Other objects and advantages of the invention will be apparent from the following description, the appended claims and the accompanying drawing, in which,

Fig. 1 is a front elevation of a crusher roll that may be employed in accordance with the present invention to form the surface of the grinding wheel shown in Fig. 2;

Fig. 2 is a side elevation showing how the formed grinding wheel is employed to grind a form tool;

Fig. 3 shows the first crusher roll after it has been trued to its original shape following a period of wear;

Fig. 4 is a section on the line 4—4 of Fig. 2 showing the form tool;

Fig. 5 shows the form tool cutting a second crusher roll;

2

Fig. 6 shows the second crusher roll and its use in forming a second grinding wheel;

Fig. 7 shows how the second grinding wheel is used to grind one of a pair of interfitting members;

Fig. 8 shows how the first grinding wheel is used in grinding the other interfitting member;

Fig. 9 shows a portion of a lamination die constructed of members produced by one of the grinding wheels and adapted for exact interfitting relationship with the other member or members ground in accordance with the present invention; and

Fig. 10 is a side view showing the ground punch.

The drawing, in which the same parts have been designated by the same reference letters or numerals, shows the various steps preferred in carrying out the present invention, in the manufacture of a pair of matched grinding wheels of exactly complementary peripheral shape. As herein shown and described, the grinding wheels are used in the manufacture of cooperating interfitting parts such as punches and dies, or the like, although it will be obvious that associated interfitting members other than simply punches and dies can be made. For example, the method

may be used in grinding broaches or laps and the part that fits in the broached or lapped passage. The method of this invention is particularly adapted for use in the construction of irregularly shaped cooperating members having a precise fit with one another and where small differences in the shape of the interfitting members may be of importance. In the manufacture of punches and dies, for example, the punch shape should conform exactly with the shape of the die into which it operates so that its clearance in the die will be uniform all the way around the punch. Heretofore the manufacture of one of a pair of accurately interfitting members has been comparatively simple but the manufacture of the second member, to have it properly interfit with the first has been difficult and has required painstaking effort and a gradual shaping process so that one member is brought bit by bit into general conformity with the other. This gradual shaping process, especially in its final stages, is usually done by lapping, which is

quite slow and tedious. In the case of dies for punching thin stock it is necessary to have a very close clearance between the male and female member of the die set, for if the clearance is too large at any particular portion or portions, there will be a burr on the stamping at these portions. An extremely close fit is often required,

also, in applying ground parts in broached passages.

Fig. 1 of the drawing shows a rotatable hard abrasion-resistant crusher roll *a* adapted to be mounted for rotation about its own axis in pressure engagement with a grinding wheel, the grinding wheel or the crusher roll being driven comparatively slowly and the two members operating at the same peripheral speed while the grinding wheel is mounted in the grinding machine in which it is used. Thus the surface of the grinding wheel, which has abrasive grains embedded in a crushable bond, is crushed or formed to have a shape which is exactly complementary to the peripheral sectional shape of the crusher roll. The crusher roll *a*, which is preferably made of steel, may be accurately ground by a rapidly rotating grinding wheel operating against the slowly rotating crusher roll, the grinding edge of the grinding wheel employed for this purpose being controlled in a precise manner by a precision machine of a suitable character. The crusher roll *a* may be ground to precisely the desired shape or form in a machine, for example, of the general character disclosed in Wolfarth Patent No. 2,248,446. The peripheral sectional shape of the crusher roll *a* is so made as to conform precisely to a side of the member to be made in accordance with the process.

The crusher roll *a* crushes the grinding wheel *b* to shape its peripheral surface exactly complementary to the form given to the crusher roll *a*. In some but not necessarily all cases it may be advisable, in order to correct any wear that may have taken place on the crusher roll when it forms or crushes the grinding wheel *b*, to retouch or retrue the crusher roll *a* in the precision grinding machine in which it was originally formed, to provide the retouched crusher roll *a'*, shown in Fig. 3. This retouched or trued crusher roll is again operated in peripheral surface pressure contact with the grinding wheel *b* to true the grinding wheel so that the grinding wheel will have a form exactly complementary to the retrued and perfectly shaped crusher roll *a'*.

The perfectly shaped grinding wheel *b* is then operated in the grinding machine at comparatively high speed to grind a form cutting tool of steel or the like. This form cutting tool may be a flat bar, or it may be a circularly formed tool as illustrated. In this operation, the steel roll *c* is slowly rotated and is given a shape corresponding to the shape of the crusher roll *a'*. If, in the grinding of the roll *c*, there has been some slight unevenness or wear in the grinding wheel *b*, the latter may be trued again by the retrued crusher roll *a'*, and the retrued grinding wheel *b* used in a finishing grinding operation to perfect the surface of the roll *c*.

Having completed the grinding of roll *c*, the latter is cut or notched as indicated at 10 to provide a circular form tool as shown in Fig. 4 and this form tool is then used in a turning operation, in a lathe or mill for example, to cut or shave a crusher roll *d* of a material that can be cut by the tool but which is hard and abrasion-resistant. The crusher roll *d* may be made of a fine-grained heat-treated cast iron such as "Meehanite" metal. The surface of the crusher roll *d* is thus given a form exactly complementary to the shape of the crusher roll *a'* or the original crusher used.

The crusher roll *d* is then operated in pressure

engagement with another grinding wheel, and at the same peripheral speed by positively driving one of the two members at a comparatively slow speed of operation in the grinding machine in 5 which the parts are later ground. This forms a grinding wheel *e* having a shape which is complementary to the shape of the grinding wheel *b*. After crushing grinding wheel *e* to the approximate shape desired, if any wear by abrasion on the crusher roll *d* has slightly altered the form of that crusher roll, the crusher roll *d* can be retrued by rotating it in engagement with the stationary form tool *c*, and the retrued crusher roll *d* again operated in peripheral surface engagement with the grinding wheel *e* to true the latter to precisely the desired shape, and precisely complementary to the shape of the grinding wheel *b*.

In this way two matched grinding wheels are provided, having formed surfaces that are complementary in shape to one another.

The grinding wheel *e* is then driven rapidly and performs a grinding operation in a suitable grinding machine, for example in a surface grinder, on a bar of steel or other stock, with the bar or the grinding wheel reciprocating in the direction of the bar axis, thus forming one side of the punch *g*. The bar is then inverted and the other side of the punch ground by the grinding wheel *e*. Having completed the punch, or if desired before making the punch, the grinding wheel *b* is driven at comparatively high speed in a surface grinder or the like to grind one or more depressions in a die member or in a row 25 of die members or plates *h*. The die plates *h* may then be inverted and depressions ground on their opposite sides in the case of a lamination die or the like, and a series of these plates *h* may then be assembled on a common holding plate, 30 providing a series of die openings *j* which are of precisely the same form but complementary to the punch *g*. Any small deviations in formation of the surface of the punch are also present in the die opening, since the two are formed by 35 grinding wheels of exactly complementary form, and the punch and die will therefore interfit precisely, without requiring laborious and painstaking lapping or perfecting to obtain the nicety of fit required. It will be understood that in 40 grinding the lamination die plate *h*, the depth of grind may be controlled precisely so that the width of the die opening formed when a series of different die plates are assembled will have the exact relationship desired with respect to the 45 width of the punch. Thus, if two or three ten-thousandths of an inch clearance is desired between the punch and die at each side of the die, the depth of grind given by the grinding wheel *b* may be made that much in excess of 50 one-half the thickness of the punch *g*.

In the construction of a lamination die or a number of such dies, a large number of individual die plates and a large number of punches may be made by the grinding operations 55 as previously described, and the punches then assembled on a common mounting plate in their proper relationship with respect to the numerous openings in the lamination die assembled from the plates. If in grinding a large 60 number of these interfitting members some wear takes place in the grinding wheels *e* and *b*, the grinding wheels may again be retrued by operating them slowly in peripheral pressure contact and at the same peripheral speed with the crusher 65 rolls from which they were formed.

It will thus be apparent that interfitting or mating parts having exactly complementary shapes may be manufactured in accordance with the present invention without requiring the laborious lapping and finishing heretofore required in matching such parts together to obtain a precision fit and thin stampings produced will not have the burrs or rough edges caused by excessive clearance between the die parts at some portion or other.

While the method herein described constitutes the preferred manner of carrying out the present invention, it is to be understood that the invention is not limited to the precise steps of the method as herein set forth, and that changes may be made therein without departing from the scope of the invention which is defined in the appended claims.

What is claimed is:

1. The method of making a grinding wheel having an effective peripheral surface exactly complementary in shape to the effective peripheral surface of a first grinding wheel, comprising grinding a cutting tool with the entire effective surface of said first grinding wheel to produce on the cutting tool a complement of the entire effective surface of the grinding wheel, then in a turning operation cutting a rotatable crusher roll with said cutting tool to provide on said rotatable crusher roll a peripheral surface which is the same in form as the effective surface of the first grinding wheel, and running said crusher roll in peripheral pressure contact with and at substantially the same peripheral speed as a second grinding wheel to impress the form of the crusher roll into the peripheral surface of the second grinding wheel and thus form that surface exactly complementary to the shape of the effective peripheral surface of the first grinding wheel.

2. The method of making a pair of matched grinding wheels having formed peripheral surfaces complementary in shape to one another and the grinding wheels having abrasive grains embedded in a crushable bond, comprising making a crusher roll having an effective peripheral contour of the desired form, running a grinding wheel and said crusher roll in peripheral pressure contact at substantially the same peripheral speed to impress the effective contour of the crusher roll into the periphery of the grinding wheel and thus produce on the grinding wheel periphery throughout its width the complement of the effective contour of the crusher roll, grinding a cutting tool with the entire effective surface of said grinding wheel to reproduce on the cutting tool the entire effective contour of the crusher roll, and then in a turning operation cutting a second rotatable crusher roll by said cutting tool to produce on the second rotatable crusher roll an exact duplicate of the effective peripheral surface of the first grinding wheel.

5 ing wheel, and running the second crusher roll and a second grinding wheel in peripheral pressure contact at substantially the same peripheral speed to impress the form of the second crusher roll into the periphery of the second grinding wheel and thus form the periphery of the second grinding wheel throughout its width into a shape that is exactly complementary to the effective peripheral surface of the first grinding wheel.

10 3. The method of making a pair of matched interfitting members having complementary surfaces, comprising making a crusher roll having an effective peripheral contour of the desired form, running a grinding wheel and said crusher roll in peripheral pressure contact at substantially the same peripheral speed to impress the effective contour of the crusher roll into the periphery of the grinding wheel and thus produce on the grinding wheel periphery throughout its width the complement of the effective contour of the crusher roll, and then in a turning operation cutting a second rotatable crusher roll by said cutting tool to produce on the second rotatable crusher roll an exact duplicate of the effective peripheral surface of said grinding wheel, and running the second crusher roll and a second grinding wheel in peripheral pressure contact at substantially the same peripheral speed to impress the form of the second crusher roll into the periphery of the second grinding wheel throughout its width into a shape that is exactly complementary to the effective peripheral surface of the first grinding wheel, then grinding one 15 40 of the members by one of the grinding wheels, grinding the other member by the other grinding wheel and interfitting the complementary surfaces of the members ground by the grinding wheels.
